UNITED STATES PATENT OFFICE

JAMES HOWDEN HUME, OF LONDON, ENGLAND

FURNACE FRONT

Application filed January 4, 1930, Serial No. 418,552, and in Great Britain January 8, 1929.

This invention relates to furnace fronts for boiler furnaces adapted to be fired by exhaust gases from internal combustion engines with provision for firing by means of liquid fuel when such exhaust gases are not available.

For firing with liquid fuel there is fitted to the furnace front an oil fuel burner coaxial with an air director with which co-
operates an air valve movable relatively to the air director.

To permit of rapid change-over from one system of firing to the other, we fit to the air director a flange of large diameter which carries the quarl for use with liquid fuel, said flange and quarl being movable with the air director, so that, when the air director, flange and quarl are retracted, a wide opening for passage of exhaust gases into the furnace is provided.

Desirably the front plate is formed with a recess to house or protect the air director (when retracted) against the action of the hot waste gases passing through the furnace front into the furnace.

The figure of the accompanying drawing is a vertical section illustrating a construction according to the invention.

Referring to the drawing, 1 denotes a boiler furnace to the mouth of which is applied a double-walled front 2 presenting a passage 3 for supply of engine exhaust gases to the furnace. 4 denotes a cylindrical air director formed with the usual internal vanes 4' cooperating with the front edge of which air director is an air valve 4² telescopically mounted on a horizontal tube 5 which is sustained by the furnace front and through which may be inserted a liquid fuel burner (not shown). The air director 4 is provided with a large diameter external flange 6 on the inner face of which is disposed a quarl 7.

In operation, if the furnace is being fired by exhaust gases, the air director 4 and the valve 4² are located in retracted position as shown in chain-dotted lines so that they are housed in a recess 8 in the forward wall of the furnace front with the flange 6 abutting against said wall, the air director and valve being thus protected from the hot exhaust

gases flowing to the furnace by way of the passage 3 and a large diameter opening 9 in the rear wall of the furnace front, said opening 9 being vacated by the quarl 7 in the retracted position of the air director. 55 As shown, in the retracted position of the air director and valve, the valve is seated upon the front edge of the air director. If the furnace is to be fired with liquid fuel, the air director is advanced to the position shown 60 in full lines in the drawing so that the flange 6 abuts against the rear wall of the furnace front, the quarl 7 entering the opening 9. The valve 4² is advanced along with the air director and is then retracted therefrom to 65 present a gap G between the front edge of the air director and the cooperating face of the valve, said gap permitting passage of air into the furnace by way of the air director. A liquid fuel burner is inserted through the 70 tube 5, a blind flange 10 being removed for this purpose.

For imparting axial movement to the air director 4 the flange 6 is conveniently fitted with long bolts, 11, extending through apertures in the forward wall of the furnace front and provided with handles, 12, operable from the stoke-hold, said bolts, in addition to being movable endwise to advance or to retract the air director, being also rotatable 75 to lock the air director in advanced or in retracted position.

For imparting axial movement to the air valve 4² there is provided a draw handle 13 operable from the stoke-hold. 85

I claim:—

1. In combination with a double-walled furnace front, the rear wall presenting a furnace opening, a burner-receiving tube sustained by the forward wall of said furnace front, said tube extending axially of the furnace, an air director movable axially of said tube, said air director having a flange at its rear end, and a quarl carried by said flange and adapted to enter said furnace opening. 90

2. In combination with a double-walled furnace front, the rear wall presenting a furnace opening, and the forward wall formed with a recess, a burner-receiving tube sustained by said forward wall, said tube ex- 100

tending axially of the furnace, an air director movable axially of said tube, said air director having a flange at its inner end, and a quarl carried by said flange and adapted in one position of said air director to enter said furnace opening, said air director adapted in another position to be housed in said recess.

3. In combination with a double-walled furnace front, the rear wall presenting a furnace opening, a burner-receiving tube sustained by the forward wall of said furnace front, said tube extending axially of the furnace, an air director movable axially of said tube, said air director having a flange at its rear end, a quarl carried by said flange and adapted to enter said furnace opening, and an air valve co-operative with the opposite end of said air director.
- 20 In testimony whereof I have signed my name to this specification.

JAMES HOWDEN HUME.
